United States Patent Office

Des. 182,938
Patented May 27, 1958

182,938

COMBINED RADIANT COOKER AND DISPLAY UNIT

Henry A. Walden, Yonkers, N. Y., assignor to Hotel Corporation of America, New York, N. Y., a corporation of New York

Application November 8, 1957, Serial No. 48,381

Term of patent 7 years

(Cl. D81—10)

Fig. 1 is a front perspective view of a combined radiant cooker and display unit showing my new design, and

Fig. 2 is a fragmentary perspective view of one side thereof taken in the direction of the arrows on the line 2—2 of Fig. 1.

Fig. 3 is a sectional view taken on the line 3—3 of Fig. 2.

The outer ends of the article are plain.

I claim:

The ornamental design for a combined radiant cooker and display unit, as shown and described.
